UNITED STATES PATENT OFFICE.

ALBEN E. LUNDELL, OF NEW YORK, N. Y., ASSIGNOR TO WESTERN ELECTRIC COMPANY,
INCORPORATED, OF NEW YORK, N. Y., A CORPORATION OF NEW YORK.

TELEPHONE SYSTEM.

1,334,307.

Specification of Letters Patent. Patented Mar. 23, 1920.

Application filed December 29, 1916. Serial No. 139,514.

To all whom it may concern:

Be it known that I, ALBEN E. LUNDELL, a citizen of the United States, residing at New York, in the county of Bronx and State of New York, have invented certain new and useful Improvements in Telephone Systems, of which the following is a full, clear, concise, and exact description.

This invention relates to semi-automatic telephone systems, and more particularly to indicating arrangements employed in such systems.

In the present arrangement, if the called line is busy, the operator has no means of knowing whether the called line is at a local or at a distant exchange. This information is desirable since, in order to ascertain whether the initiated call is in that class known as "revertive calls" or in other words, a call originating on a party line to another subscriber on this party line, the operator must again ascertain the number from the calling subscriber and compare this number with the number plate associated with the jack in which the calling plug has been inserted. If the called busy line is at a distant exchange, the operator knows immediately that the call is not revertive and it will be unnecessary for her, in this instance, to again ascertain the number of the called line.

The main feature of this invention is the provision of means to operate one signal at the exchange if the called busy line is at the local exchange, and to operate a second signal at the same exchange if the called busy line is at a distant exchange.

In its specific embodiment, this invention consists of:—the provision of two signals at one of the offices of the system to indicate the busy or idle condition of called lines, an interrupting device at this office for controlling the operation of one of said signals, and an interrupting device at a second office of the system for controlling the operation of the other signal, and a device at the first mentioned office for controlling the operation of said signals.

The drawings, with Figure 2 placed below Fig. 1, with Fig. 3 placed below Fig. 2, and with Fig. 4 placed at the right of Fig. 1, diagrammatically represent a portion of a telephone system employing the present invention. Fig. 1 diagrammatically represents 55 a calling line and a district selector through

which the calling line will be extended. Fig. 2 diagrammatically represents a cord finder. Fig. 3 diagrammatically represents an operator's key set and sending device. The portion of the drawings to the left of the dotted line in Fig. 4 diagrammatically represents an incoming selecting switch; the portion of the drawings shown to the right of the dotted line in Fig. 4 diagrammatically represents a final selector switch. Both the incoming and the final selector switches are located in the same office, while the portion of the drawings of Fig. 4 included within the dotted rectangle diagrammatically indicates an incoming and a final selector switch and an interrupter located at a distant office.

In the present system a plurality of sequence switches are employed which are similar in structure to sequence switch disclosed in the patent to Reynolds and Baldwin, No. 1,127,808, and are similar in operation and function to the sequence switch disclosed in McBerty Patent No. 1,125,579. The contacts of any sequence switch are separated from the other sequence switches employed, by the confines of the drawing and by dotted lines.

The selecting switches employed in the system may be of a type disclosed in patent to Craft and Reynolds, No. 1,123,696, January 5, 1915, and the operating circuits for the switches are similar to those disclosed in Patent to Lundell, No. 1,168,319.

The present system also employs counting relays which are similar in arrangement and operation to those disclosed in the above mentioned patent to Lundell, No. 1,168,319. For brevity in description, the registers, which control the operation of the counting relays, and which are set by the depression of various keys in the key-set associated with the operator's position, have been omitted. It will be understood, however, that registers may be employed in the manner disclosed in the above mentioned patent to Lundell, No. 1,168,319.

When the subscriber at substation 105 removes his receiver from the switch hook, the line relay 106 is energized over a circuit extending from grounded battery, left-hand winding of relay 106, outer armature and back contact of cut-off relay 107, through the substation apparatus, inner armature and back contact of cut-off relay 107, right-hand winding of line relay 106, 110

to ground. The line relay 106 attracts its armature and thereby completes a local circuit for lighting the lamp signal 108. The operator on noting the lighting of this signal inserts her answering plug 109 into the jack 110, of the calling line. A circuit is thus completed from grounded battery, winding of cut-off relay 107, sleeve of jack 110, sleeve of plug 109, winding of relay 111, to ground. The relays 107 and 111 are energized and attract their armatures. The cut-off relay 107 interrupts the energizing circuit of line relay 106, which relay retracts its armature to open the local circuit of the lamp 8. The relay 111 at its inner armature establishes a circuit from ground to inner armature and front contact of relay 111, contacts 101, 102, magnet of sequence switch 100, to grounded battery, 10 to move the sequence switch 100 out of position 1 and into position 2. In position 2 of the sequence switch 100 an energizing circuit for the relay 216 is completed from grounded battery, winding of this relay, 20 contacts 203 and 202, conductor 217, contact 103, to ground. Relay 216 attracts its armatures and at its right-hand armature and front contact completes a circuit from ground through contact 204, magnet of sequence switch 200, to grounded battery. This circuit causes the sequence switch 200 to move out of position 1 into position 2. In position 2 of the sequence switch 200 the relay 216 is maintained energized over a 30 circuit extending from grounded battery, winding of relay 216, contacts 203 and 215, left-hand armature and back contact of the relay 219, to ground. A circuit is also completed for the up-drive magnet 218 of cord finder to associate an idle sending device with the cord circuit with which the calling line has been connected. The operating circuit of the up-driving magnet 218 may be traced from grounded battery, winding of magnet 218, contact 205, front contact and right-hand armature of relay 216, to ground. The cord finder elevates its brushes until the brush 221 engages terminal 222, whereupon relay 219 is energized over the 40 circuit from grounded battery, winding of the relay 219, contact 207, brush 221, terminal 222, contact 104, to ground. Relay 219 is energized and attracts its armatures. At its right-hand armature and front contact it establishes a locking circuit for itself, which may be traced from grounded battery, winding of relay 219, contact 208, right-hand front contact and armature of relay 219, brush 224, terminal 225, conductor 226, contacts 112, 113, right-hand back contact and armature of relay 114, resistance to ground. This circuit maintains the relay 219 energized until district sequence switch 100 has moved out of position 2. At 50 the left-hand armature and back contact of

the relay 219, the energizing circuit of the relay 216 is opened. If the brushes of the cord finder are properly centered on the terminals the relay 216 deenergizes. Otherwise this relay will be maintained energized 55 over a circuit extending from grounded battery, contacts 203 and 206, conducting portion of the commutator 227, commutator brush 228, to ground. When the relay 216 is deenergized and at its right-hand front contact and armature interrupts the operating circuit of the up-drive magnet 219 to stop the cord finder switch, a circuit is also completed by the deenergization of relay 216, for moving the sequence switch 200 out 60 of position 2 and into position 3. This circuit may be traced from grounded battery, magnet of sequence switch 200, contact 209, right-hand back contact and armature of the relay 216, to ground. As soon as the sequence switch 200 reaches position 3, a circuit is completed through contacts 246 and 311 for moving sequence switch 300 into 65 position 3. After the operator inserted plug 109 into jack 110 she depressed a listening key 134 to telephonically connect her head set (not shown) with the substation of the calling subscriber. She then ascertains the number of the desired line and proceeds to set it up on the key set indicated at the 70 right in Fig. 3.

In the normal operation of the system the depression of a single office key controls the first two series of impulses and the remaining five series of impulses are controlled by the depression of four keys. In the present disclosure it has been deemed simpler to show seven sets of keys for controlling the sending of the seven series of impulses.

When the operator has set up the number on her keyboard she depresses a start key 303, which causes the sequence switch 200 to move out of position 3 and into position 4, by a circuit completed from grounded battery, magnet of sequence switch 200, contact 214, start key 303 to ground. Simultaneously sequence switch 300 is moved out of position 3 and into position 4. The operating circuit for the sequence switch in this instance extends from grounded battery, magnet of the sequence switch 300, contact 304, start key 303 to ground.

The line relay 115 is also energized at this time over a circuit which may be traced 120 from grounded battery, winding of line relay 115, contacts 116, 117, 118 and 119, conductor 120, terminal 229, brush 230, conductor 232, outer armature and back contact of relay 309, winding of stepping relay 125 302, contact 315 to ground. The line relay attracts its armatures and at its right-hand armature and front contact completes a locking circuit for itself, which is not broken until sequence switch 100 leaves po- 130

sition 5. This circuit may be traced from grounded battery, right-hand winding of line relay 115, contact 121, right-hand front contact and armature of relay 115 over the circuit previously described, to ground at contact 315. At the left-hand front contact and armature of the line relay 115 a circuit is completed from grounded battery, magnet of sequence switch 100, contacts 139 and 125, left-hand front contact of relay 115, left-hand back contact of relay 114 to ground for moving the sequence switch 100 into position 3. In this position of sequence switch 100 an energizing circuit for the up-drive magnet 122 is completed from grounded battery winding of magnet 122, conductor 123, contacts 124 and 125, left-hand front contact and armature of line relay 115, left-hand back contact and armature of relay 114, to ground. As the district selecting switch elevates its brushes over the terminals of the trunks terminating at the switch, it also elevates its commutator brushes 127, 128 and 129. As the commutator brush 128 encounters conducting segments 130 of the commutator, a circuit is completed for shunting the stepping relay 302 in the well-known manner. This circuit may be traced from ground, commutator brush 128, conducting segments 130 of the commutator, conductor 131, contacts 132 and 133, right-hand front contact and armature of line relay 115, contact 121, right-hand winding of relay 115, to grounded battery.

In position 4 of sequence switch 300 the first of a series of counting relays is actuated in the well-known manner to control brush selection at the district selector switch. The series of counting relays is actuated until the upper zero counting relay 309 attracts its armature and interrupts the fundamental circuit, above described. This relay also completes a circuit for moving the sequence switch 300 out of position 4 into position 6. This circuit may be traced from grounded battery, magnet of sequence switch 300, front contact and inner armature of the relay 309, contact 311 in position 4, to ground.

When the fundamental circuit is interrupted, line relay 115 retracts its armatures and at its left-hand armature and back contact completes a circuit for moving sequence switch 100 out of position 3. This circuit may be traced from grounded battery magnet of sequence switch 100, contact 134, left-hand back contact and armature of relay 115, left-hand back contact and armature of relay 114, to ground. In position 4 of the sequence switch 100 the tripping magnet 176 is energized to trip a proper set of brushes. The energizing circuit of magnet 176 extends from grounded battery, winding of magnet 176, contact 177, to ground. The

line relay is simultaneously energized over a circuit extending from grounded battery, right-hand winding of line relay 115, contacts 116, 117, 118 and 119, conductor 120, over the remainder of the fundamental circuit previously described. Line relay 115 attracts its armatures and at its left-hand armature and front contact completes a circuit for moving the sequence switch 100 out of position 4. This circuit may be traced from grounded battery magnet of sequence switch 100, contacts 139 and 125, left-hand front contact and armature of relay 115, left-hand armature and back contact of relay 114, to ground. In position 5 of the sequence switch 100, the fundamental circuit is re-established causing relay 115 to attract its armatures. The up-drive magnet 122 is thereupon energized to elevate the brushes into operative relation to the selected group of trunks over a circuit established from grounded battery, winding of relay 122, conductor 123, contacts 124 and 125, left-hand front contact and armature of relay 115, left-hand back contact and armature of relay 114, to ground. As the selector elevates its brushes, commutator brush 129 closes a circuit to short circuit the stepping relay 302 through conducting portions 135 of the commutator, contacts 137 and 118, right-hand front contact and armature of relay 115, contact 121, right-hand winding of line relay 115, to grounded battery. Each time that the stepping relay 302 deenergizes as a result of the closing of shunt circuit described, a pair of counting relays is actuated (in the well-known manner) until the upper zero counting relay 309 interrupts the fundamental circuit at its outer left-hand back contact and armature. The line relay 115 then retracts its armatures and at its left-hand back contact and armature closes a circuit for moving sequence switch 100 out of position 5 into position 6. This circuit extends from grounded battery, magnet of sequence switch 100, contact 134, left-hand back contact and armature of relay 115, left-hand back contact and armature of relay 114, to ground. The line relay 115 is again energized over a circuit extending from battery, right-hand winding of relay 115, contacts 121 and 138, right-hand back contact and armature of relay 114, resistance to ground. The line relay at its left-hand front contact and armature then completes a circuit for moving sequence switch 100 into position 7, which circuit extends from grounded battery, magnet of sequence switch 100, contacts 139 and 125, left-hand front contact and armature of relay 115, left-hand back contact and armature of relay 114, to ground. It will be noted that the test terminals of busy trunk lines are connected to ground. While the sequence switch 100 is rotating out of position 130

tion 6, and during the hunting operation of the district selector switch the line relay 115 is maintained energized over a circuit extending from grounded battery, right-hand winding of relay 115, contact 121, right-hand front contact and armature of relay 115, contacts 118 and 178, test brush 179, through the test terminals of busy trunks to ground. Also in position 7 the up-drive magnet 122 is again energized over a circuit extending from grounded battery, winding of magnet 122, conductor 123, contacts 124 and 125, left-hand front contact and armature of relay 115, left-hand back contact and armature of relay 114, to ground. Commutator brush 127 and centering commutator segments 140 maintain the relay 115 energized until the brushes of the district selector 126 are accurately centered on the terminals of the selected trunk. The energizing circuit of relay 115 in this instance extends from grounded battery, contact 184, left-hand winding of relay 115, commutator segments 140, commutator brush 127 to ground.

When an idle trunk has been found and the wipers of the selector switch have been properly centered on the trunk terminals, the line relay 115 deenergizes and thereby completes a circuit for moving the sequence switch 100 out of position 7 into position 8. This circuit extends from grounded battery, magnet of the sequence switch 100, contact 134, left-hand back contact and armature of relay 115, left-hand back contact and armature of relay 114, to ground. The line relay 115 is again energized over a circuit established from grounded battery, winding of relay 115, contacts 121 and 138, right hand back contact and armature of relay 114 to ground. Relay 115 when energized closes a circuit from grounded battery, magnet of sequence switch 100, contacts 139 and 125, left-hand front contact and armature of relay 115, left-hand back contact and armature of relay 114, ground, to move sequence switch into position 11. As soon as the test brush 179 engages the test terminal 180 of the selected trunk, the relay 470, which controls the release of the incoming selector switch 412, is energized over a circuit established from grounded battery, winding of relay 470, test terminal 180, test brush 179, contacts 181 and 113, right-hand back contact and armature of relay 114 to ground.

In position 11 of the district sequence switch 100, the fundamental circuit is extended to the incoming switch shown in the left-hand portion of Fig. 4. This circuit extends from grounded battery, winding of line relay 404, contact 403, conductor 402, terminal 145, brush 144, contacts 143 and 119, conductor 120, terminal 229, brush 230, conductor 232, outer armature and back contact of relay 309, stepping relay 302, contact 313 of sequence switch 300 (now in position 8), conductor 214, brush 233, terminal 231, conductor 142, contacts 141 and 146, brushes 147, terminal 148, conductor 149, contact 405 to ground. Line relay 404 attracts its armature and thus completes a circuit for moving sequence switch 400 out of position 1 into position 2. This circuit may be traced from grounded battery, magnet of sequence switch 400, contact 406, front contact and armature of line relay 404 to ground. In position 2 of the sequence switch 400 an operating circuit for the up-drive magnet 407 is completed from grounded battery, winding magnet 407, contact 408, front contact and armature of relay 404 to ground. As the selector 412 elevates its brushes, the commutator brush 409 encounters conducting segments 410. The line relay 404 is maintained energized and the stepping relay 302 is shunted over a circuit extending from grounded battery, winding of relay 404, contact 411, conducting segments 410, commutator brush 409 to ground. For each conducting segment 410 encountered by the commutator brush 409, a pair of counting relays is actuated to control the brush selection at the incoming switch. When the series of counting relays has been actuated, the relay 309 attracts its armatures and the fundamental circuit is interrupted, causing the line relay 404 to deenergize. This completes a circuit for moving the sequence switch 400 out of position 2 into position 3, which circuit may be traced from grounded battery, magnet of sequence switch 400, contact 413, back contact and armature of line relay 404 to ground. In position 3 of the sequence switch 400 the brush tripping magnet 414 is energized over a circuit extending from grounded battery, winding of tripping magnet 414, contact 415 to ground. The fundamental circuit is again reestablished and the line relay 404 attracts its armature to again close the operating circuit of the up-drive magnet. When now the brushes of the selector switch 412 are again elevated, the commutator brush 409 encounters a conducting segment 416 for each group passed by the switch. Each time that the commutator brush encounters a conducting segment 416, line relay 404 is maintained energized and stepping relay 302 is short-circuited to actuate a pair of counting relays in the manner indicated. When the series of counting relays is again actuated to energize the upper zero counting relay 309, the fundamental circuit is interrupted, causing the line relay 404 to retract its armature. This closes a circuit from grounded battery, magnet of sequence switch 400, contact 413, back contact and armature of relay 409 to ground, to move the sequence switch out of position 4. It is assumed that the selector switch 412 will now hunt for an idle trunk in the selected group. This operation, how-

ever, is not described since it is now well-known in the art. When the brushes 417, 418 and 419 have been placed in engagement with the terminals 420, 421 and 422 of the selected trunk, the fundamental circuit is extended to the final selecting switch. The relay 423 is energized over a circuit extending from grounded battery, winding of relay 423, terminal 422, brush 419, contact 424 to ground, to prevent the release of the final switch until the incoming switch has been restored to normal position. When the fundamental circuit is extended to the final switch over the contacts 425 and 426, the line relay 427 is energized and attracts its armature. This completes a circuit for moving the sequence switch 429 out of position 1 and into position 2.

In position 2 of the sequence switch 429, the up-drive magnet 430 becomes energized over a circuit extending from grounded battery, winding of magnet 430, contact 431, front contact and armature of line relay 427 to ground. The final selector switch 432 elevates its brushes 433, 434, 435 and also elevates the commutator brushes 436, 430. The brush 436 encounters the conducting portions 437 and 441 of the commutator 438, and the brush 430 encounters the conducting portions 450 and 440. As the brush 436 encounters the conducting segments 437 the line relay 427 is maintained energized and the stepping relay 302 short-circuited by a circuit extending from grounded battery, winding of relay 427, contact 439, conducting segments 437, commutator brush 436 to ground. This shunting of the stepping relay actuates the chain of counting relays to determine the brush selection at the final selector switch. When the zero counting relay 309 is actuated, the fundamental circuit is again interrupted to cause the deenergization of the line relay 427. This completes a circuit from grounded battery, magnet of sequence switch 429, contact 440, back contact and armature of line relay to ground to move sequence switch 429 into position 3. The fundamental circuit is again reestablished and the line relay attracts its armature, thereby completing the circuit for moving the sequence switch out of position 3. This circuit extends from grounded battery, magnet of sequence switch 429, contact 428, front contact and armature of relay 427 to ground. In position 4 of the sequence switch 429, the up-drive magnet 430 is again energized over a circuit extending from grounded battery, winding of magnet 430, contact 431, front contact and armature of relay 427 to ground. The selector switch 432 again elevates its brushes, which causes the commutator brush 436 to engage the conducting segments 441 of the commutator to control the group selection of the switch. As the brush 436 en-

counters a conducting segment 441 for each group of trunks passed over, the stepping relay is short-circuited to actuate the counting relays. When the series of counting relays have been actuated and the fundamental circuit again opened, the line relay 427 deenergizes. A circuit is now completed from grounded battery magnet of sequence switch 429, contact 440, back contact and armature of relay 427, to ground, to move the sequence switch out of position 5. The fundamental circuit is again reestablished with the resultant energization of the line relay 427. A circuit is thereupon completed for moving the sequence switch 429 into position 6. This circuit extends from grounded battery, magnet of sequence switch 429, contact 428, front contact and armature of relay 427, to ground. In position 6 the up-drive magnet 430 is again energized over a circuit extending from grounded battery, winding of magnet 430, contact 431, front contact and armature of relay 427. The final selector switch 432 again elevates its brushes, and the commutator brush 436 encounters the conducting segments 441 controlling the units selection. In the setting of the selector brushes 433, 434 and 435 on the terminals 442, 443 and 444 of the desired line, in accordance with the units series of impulses, the fundamental circuit is interrupted, causing the line relay 427 to deenergize.

It will be understood that when the upper zero counting relay 309 attracts its armatures at the closure of each series of impulses, an operating circuit is completed for the sequence switch 300, which circuit extends from grounded battery, magnet of sequence switch 300, front contact and inner armature of relay 309, contact 311, to ground. At the close of the units series of impulses, when the relay 309 attracts its armatures to complete the circuit just described, the sequence switch 300, which in the operation of the sender has been advanced to position 16, now moves out of this position and under the control of its master contact moves into position 1.

While the sequence switch is rotating through positions 17 and 18, a circuit is completed from ground, contact 312, conductor 316, magnet of sequence switch 200, to grounded battery, to move this sequence switch out of position 4 and into position 8. In position 8 of sequence switch 200, a circuit is completed from ground, contact 235, brush 236, terminal 247, conductor 223, contact 185, magnet of sequence switch 100 to grounded battery, to move the sequence switch out of position 11 and into position 12. When the sequence switch 100 moves out of position 11 the energizing circuit of the relay 219 is interrupted at contact 112.

As soon as the sequence switch 300 reaches

position 1 a circuit is completed for the down-drive magnet 238, which circuit extends from grounded battery, winding of magnet 238, conductor 239, contact 317, contact 240 to ground. As soon as the cord finder 220 reaches its normal position, a circuit is closed from ground, commutator brush 241, conducting segment 242 of the commutator, conductor 243, contact 244, magnet of sequence switch 200 to grounded battery, to move this sequence switch out of position 8 into its normal position. The cord finder and the sender are now in condition for operation in completing another call. 10 The sequence switch 100 is advanced through positions 12 and 13 into position 14 over a circuit completed from grounded battery, magnet of sequence switch 100, contacts 186 and 187, back contact and armature of relay 158 to ground. Under the control of its master contact 191 sequence switch 100 rotates into position 15. 15 Immediately after the deenergization of line relay 427 and while the sender and cord finder are being restored to their normal position and while the sequence switch 100 is being advanced to position 14, a circuit is completed from ground, armature and back contact of this relay, contact 440, winding of sequence switch 429 to grounded battery. 20 The sequence switch 429 is thus moved out of position 6 and continues to rotate until it reaches position 14. When the sequence switch 429 is rotating through positions 8 to 14, if the desired line is busy, this condition will be indicated by reduced potential on its test terminal 444 caused by another final selector in connection with the line. 25 The test relay 446, which is marginal, will not be energized in the test circuit which may be traced from grounded battery, resistance, terminal 444, brush 435, contact 447, through both windings in series of relay 446 to ground. When the sequence switch 429 reaches position 14, with test relay 446 deenergized, a circuit is completed from ground, left-hand armature and back contact of test relay 446, contacts 481 and 477, winding of down-drive magnet 449 to grounded battery. 30 When the commutator brush 480 encounters the conducting segment 450, a circuit is completed from ground through this commutator brush and conducting segment, contact 457, magnet of sequence switch 429 to grounded battery, to move the sequence switch out of position 14 and into position 17. In position 17 of the sequence switch 429, an interrupter, generally designated 452, is connected to contact 453, to control the actuation of a signal at the office in which the call originated. 35

In the present description the call has been extended to a subscriber whose telephone line terminates in the same office as the calling line. At the upper portion of Fig. 4

there is diagrammatically indicated within the dotted rectangle, the trunk lines and incoming and final selector switches through which the call may be extended to a distant office. 70

In accordance with the present invention, if it is found that the desired line terminating in the same office is busy, it is desired to indicate this fact to the operator. If the desired line at a distant office is busy, it is 75 desired to give the operator a different signal to inform her of this condition. For this purpose it is proposed to employ the signal lamps 150 and 151 to perform these functions. In the former systems the lamp 80 150 serves as the calling supervisory signal, and the lamp 151 flashes until the sender has been disconnected from the cord with which it is attached, but burns steadily to indicate that the called subscriber is being 85 rung, and is immediately extinguished as soon as the called subscriber answers. In addition to these indicating operations it is proposed to light lamp 151 to indicate when a desired line that is busy, terminates in the 90 local exchange, and to light the lamp 150 to indicate when a desired busy line is at a distant exchange. This indicating operation is employed in distinguishing so-called re- 95 vertive calls. 95

For the control of the lamp signals 150 and 151, two interrupters 452 and 454 are employed. It is thought that the description of interrupter 452 will be sufficient for a clear understanding of the interrupter 454. 100 The interrupter 452 comprises a constantly rotating shaft 455, on which there are mounted disks 456, 457 and 458. The disk 456 is formed of conducting material, but its surface is provided with uniformly spaced 105 insulated portions which serve to interrupt the circuit through the brush 459. The disk 457 is also formed of conducting material, but its periphery, with the exception of conducting portion 460, is covered with insulating material. Disk 458 is similar in construction to disk 457, but its conducting portion 461 is so positioned that the circuit extending through its brush 462 is not completed until the circuit extending through 110 the conducting portion 460 and brush 463 has been interrupted. The interrupter 454 is preferably constructed to interrupt its circuits in different time intervals from the interrupter 452. 115

In position 17 of the sequence switch 429 a flashing circuit is completed from ground through the disk 456, brush 459, contact 453, terminal 421, brush 418, contact 464, conductor 149, terminal 148, brushes 147, contacts 146 and 152, supervisory relay 153, winding of repeating coil to grounded battery. Since this circuit is alternately open and closed at the disk 456 and brush 459, the supervisory relay 153 vibrates its arma- 120 125 130

ture. When the relay 153 attracts its armature a circuit is completed from ground, front contact and armature of relay 153, contact 182, right-hand winding of relay 115 to grounded battery. The relay 115 at its right-hand front contact and armature controls a break-point in the circuit extending from ground through conducting portion 469 of the disk 456, brush 463, conductor 465, contact 154, right-hand front contact and armature of relay 115, conductor 155, contacts 156 and 157, winding of relay 158 to grounded battery. The relay 115, at its right-hand back contact and armature controls a break-point in the circuit extending from ground, conducting portion 461 of the disk 458, brush 462, conductor 466, contact 159, right-hand back contact and armature of relay 115, conductor 155, contacts 156 and 157, winding of relay 158 to grounded battery. It should be noted that the relay 158 is not energized to close the operating circuit for moving the sequence switch 100 out of position 15 when the called line terminates at the local office. This is controlled by the interrupter 452. The conducting portions of the disks 456 and 460 are so arranged that the circuit through brushes 463 and 459 are not closed simultaneously. For this reason, when the supervisory relay attracts its armature to energize the relay 115, the circuit through conductor 465 and the right-hand front contact of relay 115 will be open at the brush 463, in which case relay 158 will not be energized. When the energizing circuit of the supervisory relay 153 is opened, with the result that the relay 115 deenergizes, the circuit extending from grounded battery, winding of relay 158, contacts 157 and 156, conductor 155, right-hand armature and back contact of relay 115, contacts 159 and 466, brush 462, disk 458 to ground, will be open at the brush 462, which at this time will be out of engagement with conducting portion 461 and disk 458. It will thus be seen that when the called busy line terminates in the local exchange the relay 158 will not be energized and the sequence switch 100 remains in position 15 until the operator removes the plug 9 from the jack of the calling line.

While the sequence switch 100 remains in position 15 a circuit will be closed for lighting the lamp 151. The circuit extends from grounded battery, resistance, through lamp 151, contact 162, left-hand back contact and armature of relay 115, left-hand back contact and armature of relay 114 to ground.

When the called busy line terminates at a distant office the interrupter 454 will control the energization of the supervisory relay 153. This controlling circuit will extend from ground, disk 468, brush 469, con-

ductor 467, the terminal and brush 480 of the incoming selector switch at the distant office, conductor 481, terminal 192 and brush 147, contacts 146 and 152, winding of the supervisory relay 153, winding of the repeating coil to grounded battery. In this case the energizing circuit for the relay 158 is completed as follows: The supervisory relay 153 is caused to vibrate its armatures by a circuit extending from ground, disk 468 and brush 469 of interrupter 454, contact 483, conductor 467, brush 480 of the incoming switch at the distant office, conductor 481, terminal 192, brushes 147 of the district selector 126, contacts 146 and 152, relay 163 to grounded battery. As previously stated the interrupter 454 breaks the circuits which it controls in different time intervals from the interrupter 452. The supervisory relay 153 now controls line relay 115, causing this line relay to close, at its right-hand armature, break points in conductors 465 and 466, at the same time that the other break points in these conductors are closed at interrupter 452. Relay 158 is energized over either of conductors 465 and 466 and attracts its armature. A circuit is thereby closed for moving the sequence switch 100 out of position 15 into position 16. This circuit may be traced from grounded battery, magnets of sequence switch 100, contacts 139 and 164, front contact and armature of the relay 158 to ground. In position 16 a circuit is closed for flashing the lamp 150 until the operator removes plug 109 from jack 110. This circuit is established from grounded battery, resistance, the lamp 150, contact 165, left-hand back contact and armature of relay 115, left-hand armature and back contact of the relay 114 to ground.

When the operator removes the plug 9 from the jack 10 of the calling line, and then depresses wipe-out key 166, the relay 114 is energized in the circuit extending from grounded battery, contact 167, left-hand winding of relay 114, wipe-out key 166 to ground. The relay 114 attracts its armatures, and at its right-hand armature establishes a locking circuit for itself which may be traced from grounded battery, contact 168, right-hand winding of relay 114, right-hand front contact and armature of the relay 114, resistance, to ground. At the left-hand armature and front contact of this relay a circuit is closed from ground, contact 169, magnet and sequence switch 100 to grounded battery, to move the sequence switch from the position in which it is then at rest, that is, either position 15 or 16, into position 18. In position 18 of the sequence switch 100 an energizing circuit for the down-drive magnet 170 is completed from grounded battery winding of magnet 170, contacts 171 and 172 to ground. When the

commutator brush 129 encounters the normal conducting segment 173, a circuit is closed from ground through this commutator brush and contact, conductor 174, contact 175, sequence switch 100 to grounded battery. This circuit causes the sequence switch to rotate into position 1. When the relay 114 attracts its right-hand armature it opens the energizing circuit of the relay 10 470 (Fig. 4). This relay retracts its armature and completes a circuit from ground, through contact 471, magnet of sequence switch 400 to grounded battery, to move this sequence switch into position 18. In position 15 18 the incoming selector 412 is restored by magnet 482, to its normal position, in which it closes a circuit for moving the sequence switch 400 into its normal position. This circuit extends from grounded battery, 20 sequence switch 400, contacts 406 and 472, normal segment 473, commutator brush 434 to ground. When the sequence switch 400 moves out of position 16 the energizing circuit for the relay 423 is open at contact 424, 25 which causes the relay to retract its armature. A circuit is then closed from ground through armature and back contact of the relay 423, contact 476, magnet of sequence switch 429 to grounded battery, to move the 30 sequence switch into position 18. In position 18 a circuit is completed for the down-drive magnet 449, which circuit extends from grounded battery, winding of magnet 449, contact 477 and 478 to ground. 35 When the final selector switch is restored to its normal position a circuit is closed from ground, commutator brush 480, normal conducting segment 450, conductor 479, contact 457, magnet of sequence switch 429 to 40 grounded battery, to move this sequence switch into its normal position.

What is claimed is:

1. In a telephone exchange system, a plurality of lines, a plurality of offices through which said lines may be interconnected, two signals at one of said offices indicating the electrical condition of said lines, only one of which signals operates during a complete call, means at said last mentioned office which coöperates in controlling the operation of one of said signals, means at another office which coöperates in controlling the actuation of the other signal, and an automatic device for controlling the operation of both of said signals.

2. In a telephone exchange system, a plurality of lines, a plurality of offices through which said lines may be interconnected, two signals at one of said offices indicating the electrical condition of the lines, only one of which signals operates during a complete call, an interrupting device at said office which coöperates in controlling the operation of one of said signals, an interrupting device at the other office which coöperates in

controlling the actuation of the other signal, and a device at the first mentioned office for controlling the operation of said signals.

3. In a telephone exchange system, a plurality of lines, a plurality of offices through which said lines may be interconnected, two signals at one of said offices indicating the electrical condition of the lines, only one of which signals operates during a complete call, an interrupting device at said office which coöperates in controlling the operation of one of said signals, an interrupting device at the other office independent of said first mentioned interrupting device which coöperates in controlling the actuation of the other signal, said interrupting devices operating out of synchronism, and a device at the first mentioned office for controlling the operation of said signals.

4. In a telephone exchange system, a plurality of lines, a plurality of offices through which said lines may be interconnected, two signals at one of said offices indicating the electrical condition of the lines, a continuously operating interrupting device at said office which coöperates in controlling the operation of one of said signals, an interrupting device at the other office independent of said first mentioned interrupting device, which coöperates in controlling the actuation of the other signal, and a circuit-controlling device at the first mentioned office for controlling the operation of said signals.

5. In a telephone exchange system, a plurality of lines, a plurality of offices through which said lines may be interconnected, two signals at one of said offices indicating the electrical condition of the lines, a continuously operating interrupting device at said office for controlling the operation of one of said signals, an interrupting device at the other office independent of said first mentioned interrupting device for controlling the actuation of the other signal, and an auxiliary switch at the first mentioned office for controlling the operation of said signals.

6. In a telephone system, a primary office, a secondary office, lines terminating in each of said offices, an incoming line, means for extending said incoming line through said primary office to any of said lines, means for rendering any of said lines busy, automatic means at one of said offices for indicating that a busy line terminates at the primary office, and means at the same office for indicating that a busy line terminates at the secondary office.

7. In a telephone system, a primary office, a secondary office, lines terminating in each of said offices, an incoming line, means for extending said incoming line through said primary office to any of said lines, means for rendering any of said lines busy, automatic means at the primary office for indi-

cating that a busy line terminates at the primary office, and automatic means at the same office for indicating that the busy line terminates at the secondary office.

5 8. In a telephone system, a plurality of lines, a plurality of offices through which said lines may be interconnected, means for rendering any of said lines busy, two signals at one of said offices for indicating the character of said busy lines when called lines, a device for controlling the operation of either of said signals, and means for controlling the operation of said device.

10 9. In a telephone exchange system, a plurality of lines, a plurality of offices through which said lines may be interconnected, means for rendering any of said lines busy, two signals at one of said offices for indicating the busy or idle condition of said lines, a device at said last mentioned office for controlling the operation of either of said signals and a continuously operating device at each of said offices for controlling said device.

15 10. In a telephone system, a primary office, a secondary office, lines terminating in each of said offices, means for interconnecting any of said lines with any of the remaining lines, means for rendering any of said lines busy, a signal at one of said offices for indicating that a busy line terminates at the primary office and a signal at the same office for indicating that a busy line terminates at the secondary office.

20 11. In a telephone system, a primary office, a secondary office, lines terminating in each of said offices, means for interconnecting any of said lines with any of the remaining lines through said primary office, means for rendering any of said lines busy, signals at the primary office for indicating at which of said offices the busy line terminates, a device at said primary office for controlling the actuation of either of said signals, and mechanism at each of said offices for controlling the actuation of said device.

25 12. In a telephone system, a primary office, a secondary office, lines terminating in each of said offices, means for interconnecting any of said lines with any of the remaining lines through said primary office, means for rendering any of said lines busy, signals at the primary office for indicating

30 at which of said offices the busy line terminates, a device at said primary office for controlling the actuation of either of said signals, and a constantly operating mechanism at each of said offices for controlling the actuation of said device.

35 13. In a telephone system, a plurality of lines, a plurality of offices through which said lines may be interconnected, means for rendering any of said lines busy, two signals at one of said offices for indicating the character of said busy lines when called lines, a device for controlling the operation of either of said signals and timing mechanism at each of said offices for controlling the operation of said device.

40 14. In a telephone system, a plurality of lines, a plurality of offices through which said lines may be interconnected, means for rendering any one of said lines busy, two signals at one of said offices for indicating the character of said busy lines when called lines, a device for controlling the operation of either of said signals and a timing mechanism at one of said offices and means at the other office for controlling the operation of said device.

45 15. In a telephone system, a plurality of lines, a plurality of offices through which said lines may be interconnected, means for rendering any of said lines busy, two signals at one of said offices for indicating the character of said busy lines when called lines, a device for controlling the operation of either of said signals and timing mechanisms operating out of synchronism with respect to each other, located at each of said offices for controlling the operation of said device.

50 16. In a telephone system, a plurality of lines, a plurality of offices through which said lines may be interconnected, means for rendering any of said lines busy, two signals at one of said offices for indicating the character of said busy lines when called lines, a device for controlling the operation of either of said signals and timing mechanisms remotely located with respect to each other for controlling the operation of said device.

55 105
In witness whereof, I hereunto subscribe my name this 28th day of December, A. D., 1916.

ALBEN E. LUNDELL.
